CLAIM

The ornamental design for a sauce jar as shown and described.

DESCRIPTION

FIG. 1 is a perspective view of a sauce jar in accordance with a first embodiment of my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof with only a lid of the sauce jar;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is a perspective view of a sauce jar in accordance with a second embodiment of my new design.

The dashed lines in the form of a spoon and a fork depict environmental subject matter and form no part of the claimed design. The remaining dashed lines shown in FIGS. 7 and 14 depict portions of the Sauce Jar that form no part of the claimed design. The dot-dash lines in the drawings define the bounds of the claimed design and form no part thereof.
